Primary Examiner — Daniel J Domino*Assistant Examiner* — Samina Vieth(74) *Attorney, Agent, or Firm* — IPUSA, PLLC(57) **CLAIM**

The ornamental design for an antenna for wireless tag as shown and described.

DESCRIPTION

1. Antenna for wireless tag

1 Front

The dashed broken lines illustrate portions of the article and form no part of the claimed design; a back view is omitted because it is a mirror image of the front view.

1 Claim, 1 Drawing Sheet(56)
